HOLLOW CONDUCTOR

William H. Bassett, Jr., Scarsdale, N. Y., assignor
to Anaconda Wire & Cable Company, New
York, N. Y.

Application October 5, 1931, Serial No. 566,868

3 Claims. (Cl. 173—13)

This invention relates to reinforced hollow electrical conductors and more particularly to conductors of this type of large diameter.

In Bassett's Reissue Patent No. 17,156 of December 11, 1928, a hollow conductor is described in which the outer wall of the conductor is formed of a number of small diameter conducting wires laid in a helical formation to form the continuous cylindrical wall. To prevent collapse of this structure when subjected to tension, bending or other collapsing forces, a reinforcing strip of a width equal to the inner diameter of the cylindrical structure is placed within the structure and given a twist in the opposite direction to that of the wires forming the cylindrical wall, so that a supporting edge is provided at intervals in the length of each wire and at sufficiently frequent intervals to prevent an inward bending of the wire. The effect of this strip is therefore somewhat similar to that of a solid strand or supporting means within the conductor.

However, with conductors having larger diameters the supporting of the surface or cylinder forming wires against collapse by a single strip becomes increasingly difficult and less effective, as the distance between the supporting contacts of the wires on the strip increases with the diameter unless the twist of the strands is too steep or too pronounced to give the desired resistance to stretching or expansion.

An object of the present invention is to provide a supporting structure for hollow conductors, and a supported or reinforced hollow conductor, of relatively large size, without the use of an excessive amount of metal in the inner supporting structure.

In my invention I provide an internal supporting structure made up of a plurality of twisted strips so positioned and proportioned as to form, in effect, a number of strands, the effective supporting areas of which substantially fill the interior of the conductor in much the same manner as solid strands, and thus form a substantially continuous and effective compression resisting support with a minimum of metal. In the preferred form of the invention a central strand made up of a cable of small wires is employed about which the twisted strips are symmetrically arranged, thereby holding the twisted strips in assembled position with the minimum opportunity for displacement from their symmetrical arrangement. Moreover, conductors of graded diameters may be more easily obtained with standard widths of strips by

varying or adjusting the cross sectional area of the central strand.

Various features of the invention are illustrated in the accompanying drawing in which

Fig. 1 is a cross sectional view of a hollow conductor embodying the invention and showing by way of example a central strand surrounded by six twisted strips arranged in symmetrical positions.

Fig. 2 is a similar view of a conductor in which only four supporting strands are employed, and,

Fig. 3 is a view similar to that of Fig. 2 having four supporting strips, but having a central strand of small cross sectional area illustrating the supporting of a conductor of small diameter without decreasing the width of the strip.

Referring to Fig. 1 of the accompanying drawing the conductor is constructed and built about a central cable or core 10 formed of seven individual wires or strands 11. Symmetrically disposed about the central cable are six twisted strips 12 which are twisted in such a manner that the side edges of the strips lie in circular cylindrical surfaces indicated in the lines 13.

The strips 12 are, as indicated, of an I-shaped cross section. Mounted on and enclosing the structure thus formed is a circular series of outer wires 14 placed in continuous contact with each other and given a helical twist as described in the above mentioned reissue patent.

It will be observed that the areas within the circles 13 fill the space between the central cable 10 and the surface wires 14 in much the same way as would six solid cables of the same diameters. The supporting effect of this arrangement of twisted strips for the outer cylindrical wires is similar to that of a center filled with solid cables. This, however, is done without the necessity of using solid cables or strands and thus accomplishes the desired result with a minimum of metal. Moreover, the cable has greater flexibility when a number of individual strands of twisted strips are employed than would be the case if it were attempted to use a single twisted strip of a diameter equal to the inner diameter of the conductor and of a proportionate greater thickness.

The structures illustrated in Figs. 2 and 3 are similar to that of Fig. 1, except in the use of a smaller number of twisted strips and the corresponding elements are similarly numbered. As shown in Fig. 2 the areas of the line 13 need not cover the entire space within the cylinder where the diameter of the conductor is sufficiently small to prevent too great a displacement

of the strand. As is apparent from a comparison with Figs. 2 and 3 the diameter of the conductor may be decreased by merely using a central cable 10 having a smaller diameter or a smaller number of constituent wires or strands.

It will be understood that the above examples are merely for the purpose of illustration and that various modifications may be made without departing from the invention as defined in the following claims:

- 15 1. A hollow electric conductor comprising a series of wires formed into a hollow cylindrical structure, each wire having continuous contact with adjacent wires and arranged helically about the axis of said conductor to form a substantially continuous surface and a plurality of strands supporting said cylindrical structure, each strand being formed of a flat strip twisted about its own longitudinal axis so that the long dimension of the cross section of each strip is in a diametric relation to its own strand at all points along its length, said wires being of a diameter substantially less than the diameter of said strand.
- 20 2. A hollow electric conductor comprising a series of wires formed into a hollow cylindrical structure, each wire having continuous contact with adjacent wires and arranged helically

about the axis of said conductor to form a substantially continuous surface, a central core within the structure thus formed and a plurality of strands supporting said cylindrical structure, each strand being formed of a flat strip twisted about its own longitudinal axis so that the long dimension of the cross section of each strip is in a diametric relation to its own strand at all points along its length, said wires being of a diameter substantially less than the diameter of said strand.

3. A hollow electric conductor comprising a series of wires formed into a hollow cylindrical structure, each wire having continuous contact with adjacent wires and arranged helically about the axis of said conductor to form a substantially continuous surface, a central core within the structure thus formed and a plurality of strands symmetrically arranged about said core and supporting said cylindrical structure, each strand being formed of a flat strip twisted about its own longitudinal axis so that the long dimension of the cross section of each strip is in a diametric relation to its own strand at all points along its length, said wires being of a diameter substantially less than the diameter of said strand.
